KEY CASE

Lee B. Miller, West Bend, Wis., assignor to Enger-Kress Company, West Bend, Wis., a corporation of Wisconsin

Application December 24, 1938, Serial No. 247,653

1 Claim. (Cl. 150—40)

My invention relates to improvements in key cases.

One object of my invention is to provide a key container in which the keys may be quickly and easily secured in place, but when in place are so securely fastened that an act of the user is necessary to remove them, hence the chance of loss due to the key working out of the container is eliminated.

10 A further object of my invention is to incorporate my novel key container into a conventional type bill-fold or similar container.

A still further object of my invention is to provide a small accessory key container so constructed mechanically as to be receivable upon and engageable with a pocket or a margin of a pocket of a bill-fold, a similar container, a garment pocket, or the like.

20 A still further object of my invention is to provide an accessory key container in which the cost of manufacture is held at a minimum by devising the parts thereof so that a minimum of sewing will be required to construct and assemble the various parts.

25 In the drawings:

Fig. 1 is a plan view of a pocket container in which my key container is incorporated as an integral part thereof.

Fig. 2 is a plan view showing my invention as 30 disclosed in Fig. 1 with a portion of the front piece broken away to disclose the back piece and the flap folded back to show the method of insertion and removal of the keys.

Fig. 3 is a section along line 3—3 of Fig. 1.

35 Fig. 4 is a view in perspective of my accessory key container with the flap partially folded back.

Fig. 5 is a view in perspective of an accessory key container showing an alternate embodiment of my invention.

40 Fig. 6 is a plan view of a conventional type bill-fold showing my accessory key container secured in place upon a pocket thereof.

Fig. 7 is a section along line 7—7 of Fig. 1.

Fig. 8 is a cross sectional view of the accessory 45 container shown in Fig. 5 taken along line 8—8 of Fig. 5.

Like parts are designated by the same reference characters throughout the several views.

Figs. 1 and 2 show a conventional type bill-fold 50 in open position, in which a zipper opening to the bill compartment is shown at 20, and identification card pocket is shown at 21 with a transparent window 22. My device may be located opposite the identification card pocket and may form the outer wall of an additional pocket

or may be fastened directly to the bill-fold front piece 23.

As best shown in Figs. 1 and 2, my device is comprised of three major pieces, namely: a back piece 10, which may be an integral extension of piece 23, a front piece 11, and a flap 12. The front piece 11 and flap 12 are made of suitable leather or leather-like material having a degree of stiffness but adapted to provide the flexibility required in the mechanics of use of the 10 complete article. The back 10 may be of leather if it is an extension of piece 23, or may be of relatively heavy fabric when it forms the inner wall of a pocket directly under the key container thereby cutting the cost of construction, as in 15 that case the back piece 10 would not be visible.

It will be noted that flap 12 is not an integral marginal fold-over of either front 11 or back 10 but is a separate piece placed marginally coincident to edge 15 of front 11 and sewed along the 20 margin thereof of back 10, as shown by dotted line 14. Front piece 11 is provided with kerfs 16 and 16' as shown in Fig. 2, and it is seen that when keys 17 and 17' are inserted therein while flap 12 is bent back, the key heads are wedged 25 against front 11 and flap 12 is allowed to return to normal.

Due to the key heads being in close proximity to the sewed margin 15, with the result that flap 12 is distorted from its normal flat position adjacent front piece 11 into a V-shaped position, as 30 shown at 19 in Fig. 3, the resistance of flap 12 to this distortion results in the biasing of the key heads against front 11 and towards kerfs 16 and 16'. In this position the keys cannot possibly 35 work loose, but a user need only lift flap 12 to provide for easy withdrawal of the keys.

Flap 12 may be somewhat narrower than the bill-fold or container in which my invention is an integral part, and it extends over the key 40 heads substantially to the kerfs. The remaining three sides of the front and back pieces are marginally sewed.

Fig. 4 shows a further embodiment of my invention in the form of an accessory key container designed to be receivable upon and engageable with a pocket or a margin of a pocket of a bill-fold or similar container. This embodiment incorporates many features of the heretofore described integral key container, but 50 front piece 111 and back piece 110 form no part of a second container, but instead are marginally sewed to complete a separate key container. This container is sufficiently small to be received upon a pocket flap 25 of a bill-fold 31 as shown 55

in Fig. 6. Flap 112 now performs the double function of securing the keys in place by distortional stress as it forms a V-shape over the key heads as described and also serving as a wedge to secure the device to the margin of the pocket in which it is inserted as best shown in the sectional view, Fig. 7.

A further embodiment of my invention is disclosed in Figs. 5 and 8. This container is comprised of back piece 210 and flap 212, marginally sewed at 214, both of which may be identical with the corresponding parts as disclosed in Fig. 4, and a front piece 211, the lateral dimensions of which may be less than those of front piece 111 in the embodiment shown by Fig. 4. The back piece 210 now comprises the "frame work" upon which the other two pieces are secured. The front piece 211 is sewed to the back 210 by a single line of sewing 26, commencing at 27, and following a line as delineated in Fig. 5, terminating at 28 whereby to outline the structural delineations of two key receiving pockets 29 and 30, each of which is open at the top, as shown in

Fig. 5, for the reception of keys, one of which is shown in position at 31. This method of forming the pockets 29 and 30 by continuous sewing is of importance to a manufacturer because of the rapidity of which this operation may be 5 accomplished without removing the device from the sewing machine.

I claim:

A key containing device comprised of a back piece, a front piece co-extensive therewith and secured thereto, at least one kerf provided in the front piece, said kerf in spaced relation to the top margin thereof and of sufficient size to permit the insertion therein of the serrated end 10 of a key, and a separate flap seamed co-exten- 15 sively along the top of the front piece and to the back, and extending substantially to the kerf whereby said flap is distorted in V-shape over the head of the inserted key with a resultant distortion- 20 stress of the flap material biasing the key head against the front piece and toward the kerf.

LEE B. MILLER.
